Primary Examiner — Catherine S Posthauer(74) *Attorney, Agent, or Firm* — Shook, Hardy & Bacon
L.L.P.(57) **CLAIM**

The ornamental design for a pail lid, as shown and described.

DESCRIPTION

FIG. 1 is a top perspective view of a pail lid showing my new design;

FIG. 2 is a side elevation view thereof;

FIG. 3 is a top plan view thereof;

FIG. 4 is a bottom plan view thereof;

FIG. 5 is a bottom perspective view thereof; and,

FIG. 6 is a top perspective view thereof, shown in a position of use with an exemplary pail.

The broken lines are shown for the purpose of illustrating environmental subject matter of an exemplary pail and form no part of the claimed design.

1 Claim, 5 Drawing Sheets(56)
